UNITED STATES PATENT OFFICE

133,033

DESIGN FOR A PORTABLE MOTION PICTURE THEATER

Richard J. Cummins, North Pelham, N. Y.

Application March 28, 1941, Serial No. 99,952

Term of patent 14 years

To all whom it may concern:

Be it known that I, Richard J. Cummins, a citizen of Great Britain, residing at North Pelham, in the county of Westchester and State of New York, have invented a new, original, and ornamental Design for a Portable Motion Picture Theater of which the following is a specification, reference being had to the accompanying drawings, forming part thereof.

Fig. 1 is a top plan view of a portable motion picture theater, showing my new design.

Fig. 2 is a side elevational view of one side thereof.

Fig. 3 is a side elevational view of the other side thereof.

Fig. 4 is a rear elevational view thereof.

I claim:

The ornamental design for a portable motion picture theater, substantially as shown.

RICHARD J. CUMMINS.
